(57) **CLAIM**

The ornamental design for a paper product with embossing pattern, as shown and described.

DESCRIPTION

The FIGURE is a plan view of one side of a paper product with embossing pattern.

The outer rectangular broken lines depict the boundaries of the claim and form no part thereof. The dots within the boundaries of the figure form part of the claimed design. The rear side of the paper product with embossing pattern forms no part of the claimed design.

1 Claim, 1 Drawing Sheet
